UNITED STATES PATENT OFFICE.

EDWIN H. COOPER, OF LOS ANGELES, CALIFORNIA, ASSIGNOR TO C. K. SYSTEMS COMPANY, OF LOS ANGELES, CALIFORNIA, A CORPORATION OF CALIFORNIA.

LOOSE-LEAF CREDIT-BOOK.

966,736.

Specification of Letters Patent.

Patented Aug. 9, 1910.

Application filed August 24, 1909. Serial No. 514,352.

To all whom it may concern:

Be it known that I, EDWIN H. COOPER, a citizen of the United States, residing at Los Angeles, in the county of Los Angeles and 5 State of California, have invented new and useful Improvements in Loose-Leaf Credit-Slip Books, of which the following is a specification.

This invention relates more particularly 10 to that class of loose leaf account books designed to detachably hold in position on the several leaves a series of credit sales slips arranged in alphabetical order, and a main object of the invention is to provide a compact account holding book of a size that will 15 permit of easy handling, and which may be placed in a small safe or other fire proof repository.

A further object is to provide a novel 20 form of account holding book in which both sides of the leaves are utilized for holding account or credit slips, and one in which the leaves may be quickly detached therefrom and added thereto.

25 In the accomplishment of the above objects I preferably utilize a series of rectangular frames divided into a series of compartments or recesses, a metallic backing sheet being secured to the frames midway 30 of their thicknesses to form compartments on both sides. Each compartment is preferably provided with a spring bill holding clip, and each leaf has at one end thereof a hinge formed of a flexible material, to the 35 outer edge of which is secured a rigid binding strip, preferably formed of wood and of the same thickness as the leaves. The whole series of leaves being detachably secured together by suitable covers.

40 In the drawings hereunto annexed and forming a part of this specification:—Figure 1 is a perspective view of an entire book having one of the covers broken away to disclose the construction of one of the 45 leaves of the book. Fig. 2 is a longitudinal section of one of the leaves of the book. Fig. 3 is an enlarged perspective sectional detail of one of the book leaves, showing the credit slips in place in one of the compartments.

50 In modern commercial businesses a duplicate credit slip is employed when a sale of merchandise is made, the merchant keeping the original slip, while the duplicate is given 55 to the purchaser. Heretofore these original

credit slips have been filed away, and at some convenient time the bookkeeper has transferred the information contained on the original bills to a set of account books. In order to file these credit slips away so as 60 to be readily accessible at all times various filing devices have been designed, but in all instances of which I have a knowledge they have been cumbersome and of such a size that a small merchant who only possessed a small 65 fireproof safe which could not accommodate the device, has been forced to post the accounts to his set of books at the end of each day's business for fear of fire or theft.

By means of my compact credit slip holding 70 account book, the slips may be allowed to accumulate a number of days before finally posting, or statements may be rendered directly from them, as the book is of such a configuration that it may be easily placed in 75 a safe of ordinary dimensions at night.

Referring more particularly to the drawings, 5 designates a series of leaves or rectangular frames, having covers 6, 7, the whole being detachably secured together in a suitable 80 manner, but preferably by means of studs 8 rigidly secured to one edge of cover 6, the upper end of the studs being screw threaded and engaged by screw threaded caps or nuts 9. As the construction of each 85 of the leaves is exactly the same and for brevity of description I will describe only one construction.

Each leaf preferably consists of a rectangular frame formed of wooden strips 10, 90 having at each of its four corners metallic angle protectors secured thereto in a suitable manner. The inner vertical faces of strips 10 are provided with horizontally extending grooves 11 which are formed in the vertical 95 faces midway of their height. These grooves receive a metallic plate 12 preferably formed from aluminium, for the sake of lightness and durability and which forms the bottoms of a series of recesses or bill 100 holding compartments 13 on either side of the leaf. These compartments 13 are formed on either side of backing plate 12 by a longitudinally extending and centrally disposed cleat or bar 14, these bars being intersected 105 on either side by transversely disposed cross bars 15. Each bar 14 is provided adjacent each compartment with a notch 16 adapted to form a bearing seat in which a spring bill clip 17 is secured. This clip is fastened at 110

its center, each of its ends projecting into a compartment as clearly illustrated in Figs. 1 and 3 of the drawings, the bills or credit slips being inserted underneath the ends and 5 the notches 16 holding the clips from lateral movement. Secured to one of the transverse edges of frame 10, is a flexible strip 18, preferably formed of leather and which forms a connecting hinge for each leaf. The trans- 10 verse edge of this strip is secured to a rigid binding strip 19 midway of its thickness, the strips being held in detachable relation to each other by the studs 8 and caps 9 as was heretofore described.

15 It will be apparent from the above description that I have provided a compact device that will conveniently carry a large number of credit slips and which may be readily accommodated to the volume of busi- 20 ness being done.

It will be further observed that by forming the device into book form that the merchant may readily dispose of the same at night in a fire proof repository of usual 25 capacity.

What I claim is:—

1. A leaf for a credit slip book, comprising a metallic backing having flanges around 30 its edges, said flanges extending beyond each 35 of the faces of the backing, a plurality of strips secured to each of the faces of said backing, said strips forming credit slip receiving pockets, a plurality of double spring clips mounted on one of said strips, said 40 clips extending into the slip receiving pockets, a rigid binding strip secured to one edge of the backing, and a strip of flexible material for connecting the backing plate to the binding strip.

40 2. A leaf for a credit slip book, comprising

ing a rectangular frame, a backing plate mounted in said frame midway the thickness thereof, a plurality of division strips mounted on the faces of said plate, said division strips forming recesses, a plurality of 45 double ended spring clips secured to one of said division strips on each face of the backing plate, each of the recesses having a clip 50 projecting thereinto, a rigid binding strip, and flexible means for connecting said strip 55 to said frame.

3. A leaf for a credit slip book, comprising a frame provided with a backing plate, said plate being mounted in said frame midway the thickness thereof, a plurality of division strips mounted on the faces of said plate, said division strips forming recesses, a 55 plurality of spring clips secured to said division strips, each of the recesses having a clip projecting thereinto, a rigid binding 60 strip, and flexible means for securing said strip to said frame.

4. A leaf for a credit slip book comprising a frame provided with a backing plate, said plate being mounted in said frame midway the thickness thereof, a plurality of division strips mounted on the faces of said plate, said division strips forming recesses, a 65 plurality of spring clips secured to said division strips each of the recesses having a 70 clip projecting thereinto, and a binding strip secured to said frame.

In witness that I claim the foregoing I have hereunto subscribed my name this 17th day of August, 1909.

E. H. COOPER.
